SOUND AND MOVING PICTURE REPRODUC-
ING MACHINE

James W. Early and Fred H. Harrington, Los Angeles, Calif., assignors, by direct and mesne assignments, to American Reproducers Company, Los Angeles, Calif., a copartnership composed of James W. Early, J. W. G. Curtiss, Kadja V. Wolff, and Inez M. Walcott

Application March 20, 1931, Serial No. 524,008
Renewed June 30, 1934

5 Claims. (Cl. 88—16.2)

This invention relates to means for reproducing moving pictures and sounds associated with the pictures, and the principal object is to provide a machine having a universal base constructed to accommodate any of the projection heads and lamp housings now in use, and arranged with other parts so that in operation the machine has a relatively perfect balance. To that end we provide a table of very rigid construction on which a support and magazine housing are mounted with the magazine rim integral with a sound head on which a platform or base is arranged to support any of the projector heads now in use with the magazine rim also carrying a relatively rigid frame for supporting the lamp housing.

Another object of the invention is to provide a unitary means for supporting the projector head and lamp housing so that these parts can be moved in an arc to focus the lens of the projector head on a screen. To that end we provide a support on the machine table to which the magazine housing is adjustably connected so it can be turned in an arc to accomplish the focusing hereinbefore referred to. This arc adjustment of the magazine to adjust the other parts is of great importance and utility in the art as a proper focusing of the lens of the projector head can be accomplished without disturbing its relation or adjustment relative to the lamp housing as both move together when the magazine is moved in an arc.

Another object of the invention is to provide a sound and moving picture reproducing machine with means for reproducing the sounds associated with the picture both by a phonographic disk record and electrical means all built in one unit and operated by a single drive that is relatively noiseless and free from vibrations so that a nearly perfect reproduction of both picture and sound is accomplished. To that end we provide a phonograph turntable on which a disk record can be placed and the sound reproduced in a timed relation with the projection of the picture; also in the sound head we provide electrical means including exciter lamps and photolytic cell for reproducing the sounds associated with the moving picture from the sound track on the film, and the unitary drive for all of the moving mechanism of the machine is made without the use of belts and chains such as would produce sounds and vibrations that would mar the beauty of tone and faithfulness of reproduction which are outstanding features of our invention.

A feature of invention is shown in providing a lamp turntable in the exciter lamp chamber on

which a plurality of exciter lamps are arranged with manual means within easy reach of the operator for instantly turning the table to replace a burned out lamp so he will not need to stop the projection of the picture to replace it. In other words a one-fourth rotation of a hand wheel moves a burned out lamp out of focus with the photolytic cell and replaces it with a live lamp. This change can be made so quickly that there will not be a noticeable interruption in the sound record such as would destroy the beauty and balance of tone.

A feature of invention is shown in the construction of the removable gate for the film that is adjustable so it can be used with various width films. Also the gate is provided with a two-part guide wheel with one part engaged with a spring so it can yield to compensate for any unevenness of the width of the film.

Features of invention are shown in the construction, combination and arrangement of parts whereby a sound and moving picture machine is provided which in operation is relatively free from ground noise and vibration so that the reproductions of both the picture and associated sounds are relatively perfect.

Other objects, advantages and features of invention may appear from the accompanying drawings, the subjoined detailed description and the appended claims.

The accompanying drawings illustrate the invention, in which:

Figure 1 is a side view of a sound and moving picture reproducing machine that is constructed in accordance with this invention, parts that are new being indicated semidiagrammatically by full line, and the old parts indicated by dotted lines, the doors for the exciter lamp, film moving mechanism, and photolytic cell chamber being omitted for the sake of clearness in the drawing.

Fig. 2 is a plan view of the sound and moving picture reproducing machine with the projector head and lamp housing omitted, parts indicated semi-diagrammatically and showing one form of frame for supporting the projector lamp housing.

Fig. 3 is an enlarged fragmental section on line 3—3, Fig. 2, showing another form of frame for supporting the projector lamp housing.

Fig. 4 is an enlarged side view of the chambers for housing the exciter lamps, film moving mechanism and photoelectric cell with the door removed, parts indicated semidiagrammatically.

Fig. 5 is an enlarged fragmental view of a film having both a sound track and picture sections.

Fig. 6 is an enlarged fragmental side view of

60

the feed magazine with its door removed and the take-up shaft in cross section, showing the magazine adjustably secured to a support on the table so it can be turned in an arc to change the position 5 of its integral base or platform on which the projector head can be mounted, the latter being omitted for the sake of clearness in the drawings. Also indicating by dot and dash lines three of the various positions to which the platform can be 10 moved by adjusting the magazine on its support.

Fig. 7 is a plan view of the table on which the machine is mounted showing its construction relatively heavy so as to minimize vibration when the machine is in use.

15 Fig. 8 is a fragmental side view of the table showing the outward inclination of its legs that materially aid in preventing excessive vibration when the machine is in use.

Fig. 9 is an enlarged fragmental section on the 20 line 9—9, Fig. 7, showing the means for adjustably securing the legs to the table.

Fig. 10 is a semi-diagrammatic side view of the 25 film gate detached from the machine showing its guide roller mechanism adjustable to suit any width of film and also adjustable relative to properly arranging it in the machine.

Fig. 11 is a fragmental sectional view as taken on staggered line 11—11, Fig. 1, parts indicated semidiagrammatically.

30 Fig. 12 is a slightly enlarged section on line 12—12, Fig. 11, parts broken away and omitted and other parts indicated semidiagrammatically, showing how part of the gear housing can have an arc movement around the magazine take-up 35 shaft.

Fig. 13 is a section on line 13—13 of Fig 12, further illustrating the construction and arrangement of parts in the split gear housing.

The picture and sound reproducing machine 40 includes a table 10 that is adjustably supported on legs 11 that have large flat feet 12 that cover considerable space so that when the machine is arranged on a floor frictional contact between the feet and floor will prevent the machine from 45 creeping when in operation. The upper ends of the legs 11 are extended into inclined sockets 13 and are adjustably secured therein by set screws 14. By adjustment of the legs the table can be raised or lowered or adjusted side and endwise so 50 as to move the projecting and reproducing mechanism thereon into proper position relative to a focusing area such as a screen.

The top surface of the table 10 is provided with 55 raised seats 15, 16, 17 and 18 on which several of the parts of the machine are mounted and secured. A hollow shell-like support 19 having a vertical wall is secured by screw bolts 20 on the seat 15 so it stands perpendicular on the table 10, and it has a horizontally arranged bearing hole 60 21 extending through its face or closed side through which the film take-up shaft 22 is extended.

Also extended through the closed side of the support 19 are the spaced slots 23 that are concentric to the center of the hole 21 and extended through these slots are the screw bolts 24 that are secured in the inner wall 25 of the film take-up magazine 26. The bolts 24, when tightened, secure the magazine to the support, but when 70 loosened the magazine can be turned on its axis a distance equal to the degree arcs of the slots 23; and extended through the wall 25 is a hole 27 that is in register with the hole 21, and the walls of the holes 21, 27 form a bearing for the shaft 22.

75 In Fig. 6 this adjustment of the magazine 26

relative to the vertical support 19 is illustrated by full and dotted lines. Also the dot and dash line a—a shows the magazine in position for its platform 28 to support the projector head 29 in a horizontal plane; the double dot and dash line b—b shows the platform 28 inclined upward, and the triple dot and dash line c—c shows it inclined downward.

80 The purpose of tilting the platform 28 is to properly focus the lens of the projector head on a focal area such as a screen. The projector head and its lens are old in the art and for that reason are not shown or described in detail, it being understood that any suitable projector head now in use can be used with this machine.

90 The magazine 26 carries a frame 30 on which the lamp housing 31 is adjustably mounted as indicated in Fig. 1, and preferably this frame is formed by transversely arranged short pipes 32, 33 secured in bearings 34, 35 that are integral 95 with the rim of the magazine 26. A pair of parallel lamp supporting pipes 36 are spaced apart and have their inner ends extended through and secured to opposite ends of the short pipe 32, and the opposite ends of the pipes 36 are secured 100 in a union pipe 37 that is also arranged transversely of the machine. A pair of brace pipes 38 have their inner ends secured in the pipe 33 and their other ends bent inwardly toward one another and secured in the union pipe 37 adjacent the ends of the pipes 36 and these brace pipes are arranged so that they hold the lamp supporting pipes substantially parallel with the platform 28 and are mounted so that the frames move with the platform when the magazine 26 110 is adjusted on the support 19.

115 The lamp housing 31 is supported on legs 39 that terminate in clamps 40 so the housing can be moved toward or from the platform 28. If desired the pipes 36 can be provided with elongated slots 41 through which screw bolts 42 can be extended for adjustably securing the clamps 40 to the frame.

120 Preferably the ends of the cross pipes 32, 33 and 37 are closed and polished as indicated in Fig. 1. The magazine 26 also has a sound head 43 integral with its rim in which there are the aligned end and center chambers 44, 45 and 46 for the exciter lamps 47, 147 in the end chamber 44 moving or feed mechanism 48 in the center chamber 45 and photo-electric cell 49 in the end chamber 46. Also in the chamber 45 is a fire gate 50 through which the film 51 is passed into the take-up magazine 26 and wound on the shaft 22. The film 51 can be attached to the 125 shaft 22 in any suitable way, as indicated in Fig. 6, and the shaft has a tongue 122 that holds the end 150 of the film so it can be wound on the shaft 22.

130 The film moving mechanism 48, photo-electric cell 49 and fire gate 50 are all old in the art and are shown only for the purpose of illustrating the operation of the machine.

135 The exciter lamp mounting is new and comprises a turntable 52 on which four exciter lamps 47 are mounted and arranged so that if the lamp in use fails to function the operator can instantly replace it with a live lamp, by rotating the turntable a quarter turn. The turn-table 52 is secured on a shaft 53 that has its lower end journaled into the floor of the chamber 44 and has its upper end extended through the platform 28.

140 The shaft has a knurled handle 54 by which it is manually rotated to move a live lamp 47 145 in position to replace a dead one. Three of the 150

lamps 47 are idle while the other is working or in use.

The working lamp is held in operating position by means of a spring latch 55 arranged to engage the recesses 56 in the rim of the turntable 52. Also the shaft 53 is held from a too free rotation when released from the spring latch 55 by means of a spring 57 that is under tension between the adjustable collar 58 and the

10 roof 59 of the chamber 44.

The electrical current is supplied to the working lamp 147 adjacent the light tube 60 in the usual way indicated diagrammatically in Fig. 4 by the contact plug 160. The light tube 60 is old in the art, and for that reason is shown diagrammatically, its purpose, as is well known, being to conduct a strong beam of light from the live lamp 147 to the film 51 where it passes through the sound track 61 to the photolytic or 20 photo-electric cell 49 where, by means well known, the recorded sound is reproduced as the film 51 is transferred from the upper magazine 62 to the take-up magazine 26. The cell 49 is provided with an electric plug contact 149.

25 It is understood that while the film is passing from the upper to the lower magazine the machine is operating to project a picture from the head 29 to a screen not shown; and while the picture is thus being reproduced the photo-electric cell sound mechanism is operating in synchronism with the projector head to reproduce the sounds recorded on the film sound track 61. In the fragment of film 51 shown in Fig. 5 the succeeding pictures in the rectangular spaces 35 151 are not shown, as it is understood that in practice pictures are shown in these spaces.

Also in connection with the mechanism for moving the film 51 from the upper to the lower magazine there is a phonograph 163 having a 40 sound turn table 63 on which a sound record 64 can be placed and moved in time with the film 51 to reproduce the sounds that are associated with the picture of the film. In other words the machine is equipped with means for reproducing 45 sound either from the film track 61 or from the sound record 64 of the phonograph.

We provide a single means for actuating the projector head 29, film moving mechanism 48, and take-up shaft 22 in a timed relationship 50 to one another, which means includes an electric motor 66 that is mounted on and secured to the seat 16 on the table 10 so its shaft 67 is perpendicular to the table and extends both above and below it.

55 There is a driving connection between the turntable of the phonograph and the lower end of the vertically arranged shaft 67 that includes the worm gears 68, 69, shaft 70, worm gears 71, 72 and shaft 73 semi-diagrammatically indicated

60 in Figs. 1 and 2.

The upper end of the shaft 67 is in driving connection with the shaft 22 by worm gears 74 and 75 in the split housing 76. Also the worm gear 75 is in driving connection with a worm 77 on the lower end of an inclined shaft 78 that has its lower end mounted in the split housing 176 that is pivotally mounted on the shaft 22 and has a slight arc movement thereon and also in the housing 76; and also the upper end extended 70 through a housing 79 secured to the platform 28.

The housing 176 is mounted so it has an arc movement around the shaft 22 to compensate for the changed position of the magazine 26 when adjusted on its support 19. The shaft 78 also is provided with a worm and gear drive

80 for actuating the film feed mechanism 148 in chamber 48, all old and well understood in the art, and also another worm and gear drive 82—83 for driving the cross shaft 84 on which the gear 85 is mounted.

The gear 85 is arranged so it can be placed in driving connection with the feed mechanism 185 in the projector head 29, as diagrammatically indicated in Fig. 1.

85 The shaft 78 is extended through the housing 79 and has a knurled hand wheel 86 by which the shaft 78 can be manually rotated slowly when the film 51 is to be threaded down from the upper magazine 62 through the projector head 29 feed mechanism in the chamber 48 into the lower magazine 26 where it is connected to the shaft 22.

This hand wheel is placed within easy reach of the operator so he can manually rotate the various parts when replacing or removing a film or repairing broken parts.

90 The motor and driving connection to the various parts are shown diagrammatically for the purpose of illustration.

95 The magazine 26 is provided with a hinged door 87 and also the chambers 47, 48 and 49 are provided with a cover plate 88 as fragmentally indicated in Fig. 1. Also the chamber 49 is provided with a removable plug 89 that normally closes a window 90 in the rear wall of the housing 43. The plug is provided with a knurled 100 knob 91 to facilitate removing the plug when the photo cell 49 is to be removed, replaced or repaired.

105 The sounds from the record 64 can be taken off in the usual way, as by the pick-up arm 92. The record 64 is protected by a guard 93 that is supported on the posts 94 and brace 95, as indicated in Figs. 1 and 2.

110 In Fig. 10 a side view of the film gate 96 is shown. This gate is adjustable to operate with 115 films of different widths and also adjustable so it can be arranged central to the film. It is provided with a spindle 97 on which the two-piece guide spool 98 is rotatably mounted. The spindle has a relatively heavy end 99 threaded through 120 the post 100 so the spool and spindle can be adjusted toward or from the spring 101 on the other end of the spindle. The tension of the spring holds the spool against the shoulder 102 of the threaded end portion 99. The spool is 125 formed of two parts so they can be spread apart against the tension of the spring 101 to compensate for films of varied width.

130 The gate 99 is also provided with a stop screw 103 that can be adjusted to limit the inward movement of the gate when being fixed on the tongue and groove support 104 indicated diagrammatically in Fig. 4.

135 The specific construction of the gate and associated parts will be made the subject-matter for a separate application, and is shown in the application for the purpose of illustration.

140 In operation the machine is threaded up by manually turning the hand wheel 85 until the film 51 is unwound from the upper magazine in a sufficient distance to thread it through the mechanism in the chamber 48 and connect it to the winding shaft 22 of the lower magazine. The means for connecting the film to the shafts of the magazines are not shown as that mechanism is old 145 and well understood in the art.

After the film is properly connected the machine if out of focus with the screen can be focused by the means hereinbefore fully described.

When properly focused the motor can be start-

ed to actuate the mechanism to project the picture and reproduce the sound associated with it. The sound can be either taken from the film path 61 or record 64 as described.

5 We claim as our invention:

1. A sound and moving picture reproducing machine including a table, a vertical support thereon having a bearing hole therethrough, a film take-up shaft extended horizontally through

10 said bearing hole, a magazine secured to said support that is adjustable in an arc around said shaft, a sound head integral with the rim of said magazine having a film feed chamber arranged centrally therein and also a lamp and photo-

15 electric cell chambers on opposite sides of said center chamber, a film feed mechanism in said center chamber of said head that is operatively connected with said shaft, a projector head, a combined picture and sound track film in driving

20 connection with said shaft, and a motor for driving said shaft and mechanism in a timed relationship to one another so the sound track and picture film will be reproduced in exact time and harmony with one another.

25 2. A sound and moving picture reproducing machine including a table, a shell-like support having a vertical wall with a bearing hole therethrough, a film take-up shaft extended through said hole, a magazine for housing said shaft, a

30 sound head integral with the rim of said magazine that has a chamber therein, a projector head, a platform integral with said sound head, on which said projector head is secured, said magazine secured to the vertical wall of said sup-

35 port so it is adjustable in an arc around said shaft to focus the projector head on a screen, a film feed mechanism in the chamber of said head that is operatively connected with said shaft, and an electric motor for actuating said mechanism and shaft in a timed relationship with one another.

40 3. A sound and moving picture reproducing machine including a table, a shell-like support thereon that has a vertical wall with a bearing

45 hole therethrough with spaced slots therein that are concentric to the center of said bearing hole, a film take-up shaft extended horizontally through said hole, a magazine for housing said shaft, a sound head integral with said magazine

50 that has a center and end chambers therein, a projector head, a platform integral with said magazine on which said projector head is secured, screw bolts in said slots for securing said

55 magazine to said vertical wall so it can be moved in an arc around said shaft to focus the lens of the projector head on a screen, a film feed mech-

anism in the center chamber of said head for moving a picture and sound track film from the projector head through the center chamber to said shaft, means within the other chambers of the sound head for reproducing the sounds recorded on the sound track as the picture and sound film is moved by said mechanism, and a motor for actuating said shaft and mechanism in a timed relationship with one another.

4. In a sound and moving picture reproducing machine, the combination with an adjustable supporting table, a vertical shell-like support thereon, a film take-up magazine adjustably and pivotally secured to said support, a sound head integral with the rim of said magazine having end and center chambers therein, a platform integral with said sound head, a projector head secured to said platform through which a talking picture film can be passed for projection, a film feed mechanism in the center chamber of said sound head, means for actuating said mechanism in a timed relationship with the projector head, of an exciter lamp in one of the end chambers of said sound head, and a photo-electric cell for reproducing the record on said sound track as 10 the picture of said film is projected.

5. In a sound and moving picture reproducing machine, the combination with a table, a vertical support mounted on said table, a film take-up magazine adjustably and pivotally secured to 10 said support, a sound head integral with said magazine having a lamp chamber, a center chamber and a photo-electric cell chamber aligned therein, a platform integral with said sound head, a projector head secured to said platform, 11 said magazine adjustable to focus said head on a screen, a film feed mechanism in the center chamber of said sound track head for moving a picture and sound film from said projector head into said magazine, means for actuating said 11 mechanism in time with the projector head, of a turn-table in said lamp chamber, exciter lamps on said turn-table, a photo-electric cell in the cell chamber for reproducing the record on the sound track of said film, manually operable 12 means for actuating said turn-table to successively move said lamps into register with said photo-electric cell and with said sound track film and other means connected with said table and driven by said actuating means for also reproducing a sound record in time with the projection of said picture film from said head to a screen.
